UNITED STATES PATENT OFFICE.

JOHN C. SHOTTON, OF LAKewood, OHIO.

DENTAL CASTING DEVICE.

Application filed January 27, 1923. Serial No. 615,207.

The present invention relates to a dental casting device, and has for its object to provide a device of this character which embodies novel features of construction where-
5 by the castings which are used in the practice of dentistry can be made with greater ease and certainty than has heretofore been possible.

10 Dental castings are usually made of some metal such as gold, and it is necessary to use some means for forcing the molten gold to flow through the sprue opening and enter the cavity of the mold. This can be accomplished by the use of centrifugal force or by 15 the use of air pressure or air suction, the air pressure being applied to the top of the mold to force the molten metal into the same, while the air suction is applied in a reverse manner to draw the molten metal into the 20 mold.

The centrifugal process is difficult to follow when the mold is manually swung around in a sling device, and the centrifugal casting machines which have been devised are all costly and complicated. I am also aware that devices have been invented for using air pressure to force or draw the molten metal into the mold, although these devices have been complicated and the air pressure has not been under the proper control of the operator.

The object of the present invention has been to provide a dental casting device which is comparatively simple and inexpensive in its construction, which can be easily manipulated, which is under the perfect control of the operator at all times, and which enables a casting to be readily made, either by applying air pressure to the top of the mold or by producing a partial vacuum at the bottom of the mold.

For illustrative purposes I have disclosed one particular embodiment of the invention in detail, although it will be understood that many modifications and changes can be made in the details of construction without departing from the spirit of the invention, and I do not wish to be understood as restricting myself to the particular form of the invention which is shown by the drawings.

For a full understanding of the invention reference is to be had to the following description and accompanying drawings, in which—

55 Figure 1 is a side elevation of a dental casting device which is constructed in ac-

cordance with the invention, the air cup member being shown by full lines as applied to a mold resting upon an intermediate portion of the base, and being shown by dotted lines as applied to a conical shaping element which serves to smooth the plastic lining of the cup member. 60

Figure 2 is a top plan view of the base of the dental casting device, showing the conical shaping element at one end thereof and the sprue former at the other end thereof. 65

Figure 3 is a transverse sectional view through the device, showing the manner of using the device when it is utilized to provide a partial vacuum under the mold to draw the molten metal into the cavity of the mold by suction. 70

Figure 4 is a detail view of the forked arm which is applied to one side of the base and utilized for supporting the air cup in an inverted position when the device is used in the manner shown by Figure 3. 75

Corresponding and like parts are referred to in the following description and indicated on all of the views of the drawings by like reference characters.

Referring to the drawings which illustrate one of many possible embodiments of the invention, the numeral 1 designates a base member which has an elongated formation and is preferably hollow, so as to reduce the weight of the base member and save metal. The ends of the base member are shown as provided with perforated ears 2 which constitute means for securing the base to a table or other suitable support by the use of fastening members. One end of the base is provided with a substantially conical shaping member 3 having a short stem 4 projecting from the apex thereof. The opposite end of the base is provided with a sprue former 5 which is substantially conical in shape. The sprue former is removable so that different forms and shapes of sprue formers can be substituted as may be desired. The base of the sprue former is formed with a positioning pin 6 which is removably received within a corresponding opening formed in the top of the base. The apex of the sprue former is formed as usual with a recess 7 to receive the pin 8 upon which the wax pattern or matrix 9 is supported.

In preparing the mold a wax impression or pattern of the cavity in the tooth is made in the well known manner. This wax pattern 9 is supported upon the end of a pin 110

8, and the free end of the pin is inserted in the recess 7 of the sprue former 5, as indicated by dotted lines at the right hand end of Figure 1. A ring 10 of the conventional form is next placed upon the sprue former, said ring surrounding the wax pattern 9 and having the lower edges thereof in a close engagement with the top of the sprue former. The mold is now filled with a suitable investment, and after the investment has hardened the mold is subjected to a sufficient amount of heat to completely remove or burn out the wax, so that with the pin 8 removed the mold is ready for the casting operation. The general method of forming the mold is well known to the dental profession and no claim to novelty is based thereon.

The sprue former 5 leaves the mold with a depression 5^a in the top thereof, the base of the depression being in communication with the small passage 8^a which was formed by the pin 8 and which leads downwardly to the cavity 9^a which was formed by the wax pattern 9 and which has the exact shape of the wax pattern. In forming a casting a quantity of molten gold or other metal 11 must be placed in the depression 5^a and forced to flow through the passage 8^a into the cavity 9^a. This must, of course, be done quickly before the molten metal has an opportunity to cool and harden, and it must also be accomplished without the use of any excessive or violent force, such as would tend to rupture or break the material of the mold. In fact, one of the objections to some of the previous forms of devices which have been utilized for forcing the molten metal into the cavity has been that they require the use of a considerable amount of force which it is difficult to apply in such a manner as to avoid breaking or injuring the mold.

In carrying out the present invention air pressure is utilized for forcing the molten metal 11 to flow downwardly through the passage 8^a and enter the cavity 9^a. The numeral 12 designates a flared cup member which is provided with a lining 13 of some suitable plastic material, which is adapted to engage either the upper or lower edge of the ring 10 and provide an air tight joint therewith. The outer edge of the air cup 12 may be extended inwardly, as indicated at 12^a, in order to assist in holding the plastic lining 13 in place. A handle 14 projects from the back of the air cup and is formed with a passage 15 which extends entirely through the handle from end to end thereof and communicates with the air cup. The middle portion of the handle is formed with an annular enlargement or rib 14^a which may be useful in facilitating the obtaining of a firm grip thereon, and the end of the handle remote from the air cup is formed

with a seat 16 for engagement with a rubber bulb 17, the flange 17^a at the coupling end of the bulb being fitted upon a nipple 18. By suitably manipulating this bulb 17 it can be caused to act in the manner of an air pump, either to compress or attenuate the air in the air cup.

When it is desired to force the molten metal into the mold by the action of compressed air at the top of the mold, the ring 10 is placed upon the middle portion of the base 1 and the air cup 12 pressed firmly down on the upper edge of the ring, as indicated by full lines on Figure 1. The upper edge of the ring 10 is thus partially embedded in the plastic lining 13 of the air cup, with the result that a perfectly air tight joint is obtained between the cup and the ring. The middle portion of the base member 1 is provided with a series of transversely extending channels or depressions 19 which are for the purpose of providing a ready means of escape for air which may be forced through the investment of the mold, it being understood that the usual form of investment which is employed by dentists is pervious to air. The molten gold 11 having been previously placed in the depression 5^a, a squeezing or compression of the bulb 17 will now compress the air within the bulb and air cup so that the molten gold will be forced by this air pressure into the cavity of the mold. This can be done very quickly so that there will be no danger of the molten gold cooling and hardening before it can be forced into the cavity, and there is no violent or excessive pressure such as might tend to rupture the material of the mold. Care must be taken, of course, not to release the bulb 17 while the air cup is still in engagement with the ring and before the gold has had an opportunity to harden, as otherwise the return of the rubber bulb to its original position would tend to attenuate the air within the bulb and air cup and perhaps draw the gold up out of the mold cavity. Either the bulb 17 must be held in a compressed condition until after the gold has hardened, or the air cup must be disengaged from the ring before the bulb is released.

In order to smooth the surface of the plastic lining 13 and spread it uniformly over the interior of the air cup 12, the cup may be applied to the shaping member 3, as indicated by dotted lines on Figure 1. The stem 4 of the shaping member then enters the lower end of the passage 15 of the handle so that the plastic material is prevented from entering the said passage. While in this position the air cup can be rotated upon the shaping member 3 and pressed firmly downward thereon. This will result in distributing the plastic material uniformly over the interior of the

air cup and leaving the same with a smooth surface so that it will effectively engage the edge of a ring 10 to form an air tight connection therewith. Any suitable form of plastic lining may be used, although I have found that satisfactory results are obtained where a mixture of fuller's earth and glycerine are used. The use of glycerine enables a plastic material to be formed which will retain its plastic condition for a long period of time.

Under some conditions it may be found preferable to produce a partial vacuum under the mold and thereby utilize atmospheric pressure for forcing the molten metal into the mold cavity. When this is desired the air cup 12 may be supported in an inverted position by means of a bracket 20 projecting from one side of the base member 1, as indicated by Figure 3. The bracket is formed with a plug 21 which can be removably screwed into an opening 22 in the base member. The outer end of the bracket is forked and adapted to engage an annular groove or seat 23 formed at the back of the cup member. Suitable means such as a strap 24 is provided for holding the bulb 17 partially compressed. One end of the strap 24 is shown as connected to a ring 25 which is fitted upon the bracket 20, while the other end of the strap is provided with a second ring 26 which detachably engages a finger 27 at the outer end of the bracket. The plastic lining 13 is caused to engage the lower edge of the ring 10 of the mold, as indicated by Figure 3, and the molten gold or metal 11 is then placed in the depression 5^a of the mold, whereupon the ring 26 is disengaged from the finger 27. The elasticity of the rubber bulb 17 then causes it to tend to return to its normal position, with the result that the air within the bulb and air cup is attenuated. The partial vacuum which is thus produced under the mold tends to draw air through the pervious investment material, with the result that the outside atmospheric pressure acts upon the molten gold to force it into the mold cavity. This is accomplished easily and quickly without any violent effort, and there is nothing which could rupture or break the material of the mold. After the molten metal has hardened the investment material is, of course, broken and the casting obtained.

The provision of some means such as the plastic lining 13 of the air cup to obtain an air tight connection with the ring member of the mold is important where air pressure is utilized to force the molten metal into the mold cavity, and it is also important that the air pressure shall be under the complete control of the operator, since it is necessary to work quickly and get the molten gold into the mold cavity

before it has time to harden. The rubber bulb 17 provides in effect an air pump which can be utilized either for compressing or attenuating the air, according to whether it is desired to force the gold into the mold cavity by air pressure applied from the top, or draw the molten gold into the mold cavity by suction applied to the bottom. It will be obvious that various forms of such pump devices for controlling the air pressure may be used with substantially the same results and are within the scope of this invention.

Having thus described my invention what I claim as new and desire to secure by Letters Patent is,

1. A dental casting device including a ring, a mold formed within the ring of material which is pervious to air, a removable cup adapted to engage the edges of the ring, a resilient bulb connected to the interior of the cup for varying the air pressure therein, and a plastic lining arranged within the cup and adapted to have the edge of the ring embedded therein to produce an air tight connection between the ring and the cup with only a light pressure.

2. In a casting device of the character described, the combination with a mold having a body portion formed of material pervious to air, an air cup adapted to fit the mold, means for supporting the air cup, a resilient bulb applied to the cup for varying the air pressure in the same to force molten metal into the mold cavity, and releasable means for holding the bulb partially compressed.

3. A casting device of the character described, comprising an air cup adapted to fit over the ring of a dental mold, a plastic lining for the cup, and a shaping member corresponding in configuration to the size of the ring and the interior of the cup and insertable therein to shape and smooth the plastic material.

4. A casting device of the character described, comprising an air cup adapted to fit over the ring of a dental mold, a tubular handle for the cup, means communicating with the cup through the tubular handle for varying the air pressure therein when it is applied to a dental mold, a plastic lining for the cup, and a shaping member corresponding in configuration to the size of the ring and the interior of the cup and insertable therein for shaping and smoothing the plastic material, said shaping member being formed with a stem which enters the passage of the tubular handle to exclude the plastic material from the said passage.

5. A casting device of the character described, including a base having a portion of the surface thereof formed with depressions adapted to serve as air outlets at the base of a dental mold placed thereon, an air cup adapted to be applied to the top of the

dental mold, plastic material within the air cup for producing an air tight connection with the dental mold, means for producing an air pressure within the air cup to force 5 air downwardly through the previous body portion of the mold and cause molten metal to enter the mold cavity, and a shaping element projecting from the base and adapted to receive the air cup for smoothing and 10 distributing the plastic lining within the same.

6. A dental casting device for dental molds comprising a cup member, a lining for said cup member composed of plastic 15 material in which the molding member is receivable to provide a leak-proof connection, and an air connection communicating with the cup for varying the air pressure within said cup.

7. A dental casting device for dental

molds comprising a conical cup member, a lining conforming to the shape of the walls of the cup and composed of plastic material in which the molding member is receivable to provide a leak-proof joint, and 25 an air bulb communicating with the cup for producing pressure or suction within the cup.

8. Dental casting apparatus of the class described comprising a support, a forming member removably mounted thereon, a cup member adapted to coact with said forming member and having a plastic lining adapted to conform to the shape of the forming member when the latter is arranged in contacting 30 relation thereto, and an air bulb communicating with the interior of said cup.

In testimony whereof I affix my signature.

JOHN C. SHOTTON.
